TELEVISION REMOTE CONTROL OR SIMILAR ARTICLE

Douglas P. Montague, 823 W. Oakdale, Chicago, Ill.

Filed Mar. 4, 1960, Ser. No. 59,618

Term of patent 7 years

(Cl. D26—13)

Fig. 1.

Fig. 2.

Fig. 3.

Fig. 4.

Fig. 1 is a top plan view of a television remote control or similar article, showing my new design;

Fig. 2 is a side plan view thereof, the opposite side being substantially a mirror image thereof;

Fig. 3 is a front end view thereof; and

Fig. 4 is a rear end view thereof.

I claim:

The ornamental design for a television remote control or similar article, as shown and described.
